(57) **CLAIM**

The ornamental design for a multi-direction input device, as shown and described.

DESCRIPTION

FIG. 1 is a front elevational view of the multi-direction input device showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view taken from the front, left and top of the multi-direction input device.
